(57) **CLAIM**

The ornamental design for a tripod, as shown and described.

DESCRIPTION

FIG. 1 is a front, right, top perspective view of a tripod in the first state, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, top perspective view of a tripod in the second state;

FIG. 10 is a front, right, top perspective view of a tripod in the third state;

FIG. 11 is a partial enlarged view of FIG. 1;

FIG. 12 is a partial enlarged view of FIG. 2;

FIG. 13 is a partial enlarged view of FIG. 3;

FIG. 14 is a partial enlarged view of FIG. 3;

FIG. 15 is a partial enlarged view of FIG. 5; and,

FIG. 16 is a partial enlarged view of FIG. 7.

The dashed broken lines in the figures are for the purposes of illustrating portions of the tripod that form no part of the claimed design.

The dash-dot-dash broken lines are for notating enlarged views and form no part of the claimed design.

1 Claim, 16 Drawing Sheets
